(57) CLAIM

The ornamental design for a lamp head for LED streetlight, as shown and described.

DESCRIPTION

FIG. 1 is a bottom plan view of the lamp head for LED streetlight showing the new design;

FIG. 2 is a front elevational view thereof;

FIG. 3 is a left side elevational view thereof;

FIG. 4 is a top perspective view thereof;

FIG. 5 is a rear elevational view thereof;

FIG. 6 is a bottom perspective view thereof;

FIG. 7 is an exploded bottom perspective view thereof and which illustrates the internal structure of the lamp head, wherein the internal structure of the lamp head is not shown in the other figures for convenience of illustration;

FIG. 8 is a right side elevational view thereof; and,

FIG. 9 is a top plan view thereof.
